[57] CLAIM

The ornamental design for a handle for a fishing rod, as
shown and described.

DESCRIPTION

FIG. 1 is an elevational view of one side of a handle for
a fishing rod showing our new design.

FIG. 2 is a top plan view thereof;

FIG. 3 is a bottom plan view thereof.

FIG. 4 is a front elevational view thereof.

FIG. 5 is a rear elevational view thereof.

The broken line showing of the reel, reel nut, foregrip
and rod is for environmental purposes only and forms
no part of the claimed design.

FIG. 1

FIG. 2

FIG. 3

FIG. 5
